US00D868786S

(12) **United States Design Patent** (10) Patent No.: **US D868,786 S**
Fook (45) Date of Patent: **** Dec. 3, 2019**

(54) **DESKTOP SCANNER**

(71) Applicant: **Lee Seng Fook**, Singapore (SG)

(72) Inventor: **Lee Seng Fook**, Singapore (SG)

(**) Term: **15 Years**

(21) Appl. No.: **29/628,870**

(22) Filed: **Dec. 8, 2017**

(51) LOC (12) Cl. **14-02**

(52) U.S. Cl.

USPC **D14/425**; D14/424; D14/420

CLAIM

I claim the ornamental design for a desktop scanner, as shown and described.

DESCRIPTION

FIG. 1 is a perspective view of a desktop scanner in accordance with my new design, shown in a closed position; FIG. 2 is a perspective view of the desktop scanner, shown in an open position;

FIG. 3 is a left side view thereof;

FIG. 4 is a right side view thereof;

FIG. 5 is a front view thereof;

FIG. 6 is a back view thereof;

FIG. 7 is a top view of the desktop scanner in a closed position; and,

FIG. 8 is a bottom view thereof.

The broken lines depict unclaimed features of the desktop scanner that form no part of the design claim but are included for illustrative purposes.

1 Claim, 8 Drawing Sheets
